JET PROPULSION UNITS

Louis Jules Bauger, Vanves, France, and Anton Barthlème, Munich, Germany, assignors to Société Nationale d'Etude et de Construction de Moteurs d'Aviation, Paris, France, a French company

Filed May 9, 1957, Ser. No. 658,161

Claims priority, application France May 11, 1956

1 Claim. (Cl. 60—35.54)

It has already been proposed to provide jet propulsion units with jet deflecting devices comprising, for example a divergent curved guide surface disposed behind the edge proper of the outlet orifice of the propulsion unit, this surface being followed in some cases by a grate of semi-circular deflector blades. The deflection is initiated by solid or fluid obstacles disposed in the flow. On the other hand, it has also been proposed to adjust the cross-sectional outlet area of the jet by means of movable flaps.

The presence of solid deflecting obstacles in the flow, or at least the presence of the support of such obstacles, results in losses of thrust in the direct flow of the jet even when these obstacles are retracted. The present invention permits of obviating this disadvantage, and concerns a jet propulsion unit, in which the outlet orifice of the nozzle is provided with movable flaps of spherical or other form adapted to the form of the nozzle for the adjustment of the cross-sectional area afforded to the jet, as also with a deflecting device comprising a curved guide surface (advantageously followed by a grate of deflector blades) which is separated by a clearance from the edge proper of the outlet orifice, the flaps being so arranged as to be retractable into the said clearance and being adapted to take up a position one against the other in a diametral region of the nozzle in order to generate an obstacle to the axial flow of the jet and thus to deflect the latter towards the guide surface.

However, such a device would only permit relatively small variations of the cross-sectional outlet area of the nozzle, since the surface of the flaps is limited to that which is necessary for producing the deflection of the jet. The cross-sectional variation produced by these flaps would then be insufficient, especially in the case of turbo-jet units having after-combustion and comprising a jet deflector associated with the nozzle.

In such engines, the variation of the cross-section of the jet is much greater than that which is necessary in engines having no after-combustion. The simple flap then becomes insufficient to ensure the necessary cross-sectional variation between the take-off without after-combustion and take-off with after-combustion and a fortiori insufficient to ensure the cross-sectional variation necessitated by after-combustion at altitude.

Therefore, in accordance with an advantageous feature of the invention, double or multiple spherical flaps are provided which are adapted to be retracted one into the other or to be controlled independently.

The description given in the following with reference to the accompanying drawings, which are given by way of non-limitative example, will enable the manner in which the invention can be carried into practice to be readily understood, the features appearing both from the drawings and from the text naturally forming part of the said invention.

Figure 1 is an elevational view, partly in section, of the rear part of a jet propulsion unit having after-combustion and comprising a jet deflector according to the in-

2

vention, in the position with the nozzle closed for take-off without after-combustion;

Figure 2 is a similar view, but in the position for deflecting of the jet;

5 Figure 3 is a section along the line III—III of Fig. 2;

Fig. 4 is an axial section through an improved constructional form permitting notably retraction of the guide surface and of the blade grate, the device being illustrated in the position for deflection of the jet; and

10 Figure 5 shows a modified form with a fixed blade lattice and a movable outer fairing.

There will be seen in Figure 1 a jet propulsion nozzle 1, the outlet orifice of which, designated by its edge 1a, is surrounded by a circular ring 2 having an outwardly

15 flared curved surface 2a a little on the downstream side of the edge 1a. The ring 2 is followed by a series of circular deflector blades 3. The assembly comprising the ring 2 and the deflector blades 3 is fixed to the wall of the nozzle by tie rods 4. A clearance 5 is left between

20 the edge 1a and the ring 2 to create by an aspiration effect under the action of the jet an intake of external air which prevents the jet from adhering to the surface 2a when the jet is to be axially ejected, outside the deflection periods. In the position illustrated in Figure 1, two pairs

25 of spherical flaps 6a, 6b, 6'a and 6'b having different radii in each pair and pivotally mounted on a pin 7 situated in the diametral plane of the nozzle perpendicular to the plane of the figure, are disposed between the ring 2 and the terminal portion of the nozzle. The radii of the

30 said flaps are such that the flaps 6'a and 6'b can slide with slight clearance on the flaps 6a and 6b. These flaps therefore enter the clearance 5.

When these flaps are in the fully open position and completely retracted into the clearance 5, their extreme

35 downstream edges are placed at a distance greater than the diameter of the outlet edge 1a, so that the jet can flow axially from the nozzle as if there were no flaps and no deflector members.

In the position illustrated in Figure 1, the flaps have

40 been moved towards one another in such manner that they intercept certain marginal streams. Thus, as a re-

sult of a shearing effect on these flaps, there is a reduction in the total cross-section of the jet, as indicated by the

arrows representing the streams of the jet. In the posi-

45 tion of Figure 2, the flaps 6a and 6b are closed, that is to say, applied one against the other in the central zone of the jet, while the flaps 6'a and 6'b are retracted, leaving the nozzle fully open. The flaps 6a and 6b divide

50 the jet into two parts, which are taken up by the blade

grate 3 and deflected as indicated by the arrows. The

retracted flaps 6'a and 6'b uncover the guide surface 2a,

to which the deflected jet can adhere.

Figure 3 illustrates one constructional form for the

55 control of the flaps. Each of the flaps is controlled by a jack

such as 8a, 8b, the rod of which is linked by a connecting

rod 9a, 9b to a lever 10a, 10b fast with the pivot 11a, 11b

60 connected to the corresponding flap.

If desired, only the appropriate jack or jacks for ac-

65 tuating a single flap or a single pair of flaps may be fed

60 whereby an asymmetrical deflection is obtained. If, for

example, starting from the position in which all the flaps

are retracted into the clearance 5, only the jacks of the

pair of flaps 6a, 6'a are fed in order to bring these flaps

65 into the position illustrated in Figure 1, the jet is deflected

downwards with reference to Figure 1, this deflecting being

accentuated by the blade grate. A variation of the

65 direction of the thrust is thus obtained which permits of

exerting a steering couple on the aircraft.

It is always advantageous in the absence of deflection

70 to retract the members provided for this purpose on the

upstream side of the outlet orifice. For this purpose, in

the constructional form illustrated in Figure 4, the guide ring 2 is divided into two parts, one part 2a being fixed and the other 2b being movable and connected to the blades 3. The assembly comprising the ring 2b and the blades 3 can slide in an upstream direction parallel to the axis of the nozzle so as to enter the fairing 15 under the tractive action of jacks 12 connected to the ring 2b by tie rods 13 guided by rollers 14. In the upper half of Figure 4, the device is illustrated in the position for the axial ejection of the jet, the lower half of the figure illustrating the deflecting position.

In the constructional form illustrated in Figure 5, it is the fairing 15 which is movable and which moves towards the rear so as to cover, as indicated in chain-lines, the deflecting members, which are fixed, when the jet is to flow axially.

It will be obvious that modifications may be made to the constructional forms hereinbefore described, notably by substitution of equivalent technical means, without departing from the scope of the present invention.

What is claimed is:

The combination, with a jet propulsion nozzle ending with a circular outlet orifice for the discharge of a jet, of an outwardly curved convex annular surface having a minimum diameter greater than the diameter of said cir-

cular orifice, said surface extending around said orifice in radially spaced relation therewith to provide an annular gap around the periphery of said orifice and further extending axially downstream of said orifice, said gap facing substantially in an upstream-downstream direction and being open at both ends, and pivotal flaps mounted on said nozzle and movable through said gap to a retracted position wherein they lie outside the nozzle out of contact with the jet issuing from said orifice and an operative position wherein they lie across part of the path of the jet to deflect it laterally whereby a portion of the jet adheres to said convex annular surface.
